UNITED STATES PATENT OFFICE.

GEORGE W. FRAME, OF FAIRFIELD, IOWA.

NECK-YOKE.

956,634.

Specification of Letters Patent.

Patented May 3, 1910.

Application filed June 12, 1909. Serial No. 501,793.

To all whom it may concern:

Be it known that I, GEORGE W. FRAME, a citizen of the United States of America, residing at Fairfield, in the county of Jefferson and State of Iowa, have invented certain new and useful Improvements in Neck-Yokes, of which the following is a specification, reference being had therein to the accompanying drawing.

- 10 This invention relates to neck yoke centers, and the principal object of the same is to provide a simple and effective device which may be readily attached to, or detached from, a vehicle pole, and which, when 15 in position on the pole, will readily respond to all movements thereof, and further, will be so detachably locked on the pole and held in rigid engagement therewith as to be practically noiseless.
- 20 In carrying out the objects of the invention generally stated above it is contemplated employing a frame which may have a detachable engagement with a neck yoke, said frame having a pivotal and a yielding 25 engagement with a pole guide and holder, said frame also being provided with a forward resilient pole support, and with a rear arm adapted to engagement with a hold-back of a pole and also serving as a means 30 for holding the neck yoke center in engagement with a pole.

It will be understood, of course, that in carrying out the invention as generally stated above the essential features thereof 35 are susceptible of changes in details and structural arrangements, one preferred and practical embodiment of which is shown in the accompanying drawings, wherein—

Figure 1 is a perspective view of the improved neck yoke center. Fig. 2 is a rear elevation thereof. Fig. 3 is a central vertical sectional view, showing the device attached to a wagon pole.

Referring to said drawings it will be observed that the improved neck yoke center is composed primarily of a main frame having a base 1 through which a central opening 2 is formed, said central opening 2 communicating with a bottom recess 3, and its 40 upper end merging into an upper recess 4 which at its rear merges into an upstanding annular flange 5. The front portion of said recess 4 merges into a lip 6, the arrangement of lip and rear flange being such that the 45 front upper portion of the base 1 has a lip surrounding it, and the rear of said upper

portion of the base has an upstanding flange surrounding it which serves as an abutment for a holdback attachment to a vehicle pole, as will presently appear. A 50 pair of arms 7 project from the base 1, said arms being upwardly and outwardly curved, and the members of said pair of arms being oppositely disposed, and form the end supports for a semi-cylindrical neck yoke rest 55 8, the forward portion of which may be cut-away to reduce weight, and also to facilitate access to the neck yoke, said cut-away portion being designated by the numeral 9, and the ends thereof providing supports through 70 which fastening bolts or screw 10 pass which secure the said rest to a yoke.

As will be observed by reference to Fig. 3 of the accompanying drawings, the recess 4 merges into the central opening on an easy 75 outward curve and forms a bearing surface for an enlarged rounded under surface of the head 11 of a pintle 12 which projects through said central opening 2, the lower end portion of said pintle being threaded 80 as indicated at 13. The head 11 carries an upstanding vertically arranged pole supporting eye 14, the base portion of which is widened as indicated at 15 and whose front face is on an incline as indicated at 16, and 85 terminates in a rounded face shoulder 17 adapted to contact with a lip 18 depending from the front portion of the cut-away portion 9 of the yoke rest 8 to limit the forward rocking movements of said eye 14. 90 The interior of the eye is preferably lined with wear-resisting and cushioning material 19 said lining retained in position by the rivets 19^a or other fasteners. The base of said eye 14, at its rear, carries a laterally 95 projecting lug 20 which is adapted to bind with the rear flange 5 of the frame so as to limit the rotary movements of the eye 14 relative to the base 1 of said frame. A spring metal plate 21 is loosely mounted 100 upon the threaded portion 13 of the pintle 12, the forward portion of said plate being upturned to form an arm 22 the upper end of which is forked, as indicated at 23, to engage with the outer end portion of the 105 vehicle pole 24, conventionally represented in Fig. 3. The rear end of said plate carries an upstanding arm 25 the end portion of which is bent at an angle to provide a spring lip or finger 26 which engages behind a hold-back plate 27 which abuts the rear flange 5 of the base 1 of the frame, as is clearly in-

dicated in Fig. 3. A lock nut 28 for the threaded end 13 of the pintle 12 holds said plate 21 upon said pintle and in contact with the lower convolution of a coiled spring 5 29, the upper convolution of which is seated within the recess 3. Said spring is preferably a tapering one, its upper convolution being the larger convolution and fitting snugly within said recess 3.

10 The entire frame, including the yoke rest, supporting arms and base, may be cast or formed in one piece, and the eye and its pintle may also be of one piece of metal.

It will be seen from the foregoing that 15 through the described manner of mounting the pole supporting eye within the base of the frame, said eye is capable of a universal movement therein so as to adapt itself to the various movements of the vehicle pole, 20 and through the described spring pressure exerted against the plate 21, said plate is at all times held in binding engagement with the lock nut 28. Another prominent feature 25 of the invention is in the employment of said plate 21 which, by means of its end arms, forms a simple and efficient holdback engaging arm which prevents forward movement of the neck yoke center on the pole, and the forked arm 22 by its engagement 30 with said pole, serves to prevent the plate 21 turning in a manner that would release the arm 25 from engagement with the hold- 35 back.

In applying the improved neck yoke center to a pole, the same is reversed from the 35 position shown in Fig. 3, and slipped over the end of the pole until the rear flange is in alinement with the holdback attachment, whereupon the said device is returned to its 40 upright position, with its holdback attachment engaging arm behind the hold back.

What I claim as my invention is:—

1. A device of the character described comprising a main frame adapted for engagement with a neck yoke, a pole supporting eye mounted therein for universal movement, and a spring plate carried by said eye and having end arms for engaging a pole and also engaging with a holdback attachment. 45

2. A device of the character described comprising a main frame adapted for attachment with a neck yoke, a pole supporting eye having a pivotal and yielding movement therein, and a plate carried by said eye for engaging a pole and also holding said frame to said pole. 55

3. A device of the character described comprising a frame provided with a neck 60 yoke rest, a pole supporting eye pivotally and yieldingly mounted in said frame, and a plate carried by said eye and having end arms for engagement with a vehicle pole.

4. A device of the character described 65 comprising a frame, a pole supporting eye

having a universal movement therein, a plate loosely mounted on said eye, and end arms carried by said plate for engagement with a vehicle pole.

5. A device of the character described 70 comprising a frame, a pole supporting eye loosely mounted therein, a plate loosely mounted on said eye, and end arms carried by said plate for engaging a vehicle pole and also for holding said frame to a pole. 75

6. A device of the character described comprising a neck yoke frame, a pole receiving eye pivotally and yieldingly mounted therein, a plate loosely attached to said eye, end arms carried by said plate, one of 80 which engages a pole and the other adapted to hold said frame on said pole. 85

7. A device of the character described comprising a frame, a pole receiving eye mounted therein, and a plate loosely mounted on said eye and having end arms, one of 85 said arms having its free end forked to engage a pole, and the other arm having its free end bent at an angle to provide a locking finger for holding said frame on a pole. 90

8. A device of the character described comprising a frame provided with a base having a central opening and an upper and a lower recess communicating through said opening, a neck yoke rest supported by said 95 base, a pole receiving eye having a pintle projecting through said central opening, a plate mounted on said projecting portion of said pintle, a lock nut for holding said plate to said pintle, a spring coiled about said 100 pintle and interposed between the bottom recess and said plate, and end arms carried by said plate for engaging with a vehicle pole.

9. A device of the character described 105 comprising a frame provided with a base having upper and lower recesses and communicating central opening, a neck yoke rest carried by said frame, a pole receiving eye resting in the upper recess and having a 110 pintle projecting through said central opening, a plate loosely mounted on said pintle and having end arms for engagement with a vehicle pole, a lock nut for holding said plate to said pintle, and a spring interposed 115 between the bottom recess and said plate.

10. A device of the character described comprising a frame, an eye universally mounted therein, a plate loosely mounted on said eye and provided with pole engaging 120 arms, and a spring interposed between said frame and said plate.

11. A device of the character described comprising a yoke supporting frame, a pole receiving eye having a pintle mounted in 125 said frame, a spring plate mounted on said pintle and provided with pole engaging arms, and a spring interposed between said frame and said plate.

12. A device of the character described 130

comprising a frame provided with a base, arms projecting from said base, a yoke rest carried by said arms, a pole receiving eye mounted in said base, and a plate carried by 5 said eye for engagement with a pole.

13. A device of the character described comprising a frame provided with a base having a rear flange, a yoke rest supported by said base and provided with a pendent 10 lip, an eye pivotally and yieldingly mounted in said base, said eye being limited in its movements by said lip, and pole engaging means carried by said eye.

14. A device of the character described 15 comprising a frame provided with a base having an upper recess provided with a rear abutment flange adapted for contact with a holdback of a vehicle pole, a pole receiving eye universally mounted in said 20 base, and a plate mounted on said eye and

provided with a pole engaging and a holdback engaging arm.

15. A device of the character described comprising a frame provided with a base having an upper recess and a central opening, said recess merging into said opening, a rear abutment flange carried by the upper portion of said base, an eye provided with a pintle mounted in said central opening, said eye being also provided with a rounded portion which seats upon the junction of said recess and said opening, a plate mounted upon said pintle, and pole engaging arms carried by said plate.

In testimony whereof I hereunto affix my 35 signature in presence of two witnesses.
